GARMENT HANGER

Albert J. Beaulac, Fitchburg, Mass.

Application April 7, 1955, Serial No. 499,815

5 Claims. (Cl. 223—91)

This invention relates to a new and improved garment hanger which is particularly adapted for holding trousers by the cuff ends thereof, but which is useful for all garments, and the principal object of the invention resides in the provision of a relatively simple but positive holding means for holding garments without the use of spring latches but embodying positive clamping means for holding the garments so that the same cannot slip from the garment hanger.

Another object of the invention resides in the provision of a garment hanger of simple construction and comprising a central member including a pair of opposite slotted, laterally-extending wings thereon, in combination with a pair of pivoted clamping members having clamp elements extending through the slots in said wings and being provided with garment-holding elements at the ends thereof for cooperating with similar elements on the central member, providing for a double garment hanger having two clamping means, each of which is positively and independently adjusted and positively clamped relative to the other; and the provision of a device as above described including a rotatable coat hanger mounted in a novel manner thereon.

Other objects and advantages of the invention will appear hereinafter.

Reference is to be had to the accompanying drawings, in which

Fig. 1 is a view in front elevation illustrating the novel garment hanger;

Fig. 2 is an enlarged view in elevation, taken on the line 2—2 of Fig. 1, part being in section; and

Fig. 3 is an enlarged view in elevation of the clamping portion of the device, looking in the direction of arrow 3 in Fig. 1.

In carrying out the present invention, there is provided a main support or central element 10, the same being elongated and made in any convenient manner and from any suitable material, but preferably being of pressed metal and having an end perforated as at 12 for reception on a bolt indicated at 14, the bolt finding support in a U-shaped member 16, 18.

The opposite or lower end of the member 10 is provided with a twisted flat portion 20 to which may be secured by any desired means elongated cross pieces 22 which may be of wood or the like and which have secured thereto softer strips 24 such as felt or the like to grip the garments to be held by the device.

The central member 10 is provided with a pair of oppositely extending co-planar wings 26 and 28, each of which is formed on a curve of which the bolt 14 is the center. These wings are slotted as at 30 and passing through the slot there are provided screw-threaded fastener means generally indicated at 32, each of which is provided with a head 34 for tightening and loosening the same by engagement of head 34 with the surface of the wing members 26 and 28, against the arcuate side members 36 and 38.

The fasteners 32 are mounted in the arcuate side mem-

2

bers 36 and 38, the latter being mounted to swing on the bolt 14, so that the fasteners 32 ride easily in the slots 30. The member 38 is arranged partially co-planar with member 36 by being twisted slightly from the area of the fastener 14 down to the area of its wing portion 26.

By rotating the heads 34, the members 36 and 38 are clamped to the wings 26 or 28, or selectively they are loosened so as to allow swinging thereof in the direction of the arcuate arrows in Fig. 1. The member 38 is shown in Fig. 1 as being open in a position to receive a garment between the element 24 and a like element 40 at the free end of arm 38. The element 36 is shown in clamping relationship with respect to the central member and it also is provided with a similar garment clamping elongated element 40.

It will be seen that the present device positively clamps garments and will hold the same in fixed relationship, so that the garments cannot slip and fall to the floor. The clamping operation is extremely simple and may be quickly and easily accomplished merely by adjusting the positions of the side members 36 and 38 with as much clamping pressure as desired.

An arcuate coat-hanger member 42 is arranged on the base 44 of the hanger hook 46 and this coat hanger is arranged to rotate thereon, so that the coat may be positioned at any desired angle with respect to the garment hanger portion thereof, thus rendering the same more convenient particularly in crowded condition of garment storage spaces such as the ordinary closet. It is to be noted that the various members of the present invention may be made of metal, plastic or any other suitable material.

Having thus described my invention and the advantages thereof, I do not wish to be limited to the details herein disclosed, otherwise than as set forth in the claims, but what I claim is:

1. A garment hanger comprising a support, a central elongated member depending therefrom, a laterally swingable garment clamping member arranged to pivot with respect to said central member, cooperating garment gripping elements located on the central member and the swingable member transversely thereof, an elongated arcuate guide on the central member intermediate the ends thereof and crossing the pivoted member, and clamping means on the pivoted member and associated with the arcuate member for positively clamping the pivoted member in selectively adjustable angular relationship with respect to the central member, the arcuate guide having a center of curvature substantially coincident with the axis of swing of the swinging member.

2. A garment hanger as recited in claim 1 including a coat hanger rotatably mounted on said support above the central member.

3. A garment hanger of the class described comprising a support, a depending elongated central member on the support, a pair of elongated arcuated wings extending in opposite directions laterally from said central member intermediate the ends thereof, a garment clamping member swingably mounted on the central member at each side thereof, a manually manipulated clamp on each swingable member having a portion clampingly associated with a respective elongated wing for securing the same thereto in selectively adjusted angular position with respect to the central member, and garment gripping elements at the free end of each garment clamping member in corresponding relation with like elements at the lower end of the central member, the arcuate wings having a center substantially coincident with the axis of swing of the swingably mounted clamping members.

4. The garment hanger of claim 3 wherein said support comprises a downwardly opening, U-shaped member, a pivot-pin extending between the legs thereof, and

said central member and said two garment-clamping means being located on said pin and between the legs of the U-shaped member.

5. The garment hanger of claim 3 wherein said wings are arcuate and slotted and the clamp on each respective swingable garment clamping member extends through a respective slot and includes a head for clamping engagement with the wing at the opposite side thereof from that of the swinging garment clamping member.
